[57] CLAIM

The ornamental design for an overhead console for vehicles, substantially as shown and described.

DESCRIPTION

FIG. 1 is a bottom plan view of a first embodiment of an overhead console for vehicles showing my new design; FIG. 2 is a front elevational view thereof;

FIG. 3 is a top plan view thereof;

FIG. 4 is a side elevational view thereof;

FIG. 5 is a perspective view thereof;

FIG. 6 is a bottom plan view of a second embodiment of an overhead console for vehicles showing my new design;

FIG. 7 is a front elevational view of the second embodiment;

FIG. 8 is a top plan view of the second embodiment;

FIG. 9 is a side elevational view of the second embodiment;

FIG. 10 is a perspective view of the second embodiment;

FIG. 11 is a bottom plan view of a third embodiment of an overhead console for vehicles showing my new design;

FIG. 12 is a front elevational view of the third embodiment;

FIG. 13 is a top plan view of the third embodiment;

FIG. 14 is a side elevational view of the third embodiment; and

FIG. 15 is a perspective view of the third embodiment.
